(57) **CLAIM**

The ornamental design for an electrical connector as shown and described.

DESCRIPTION

The patent or application file contains at least one drawing executed in color. Copies of this patent or patent application publication with color drawing(s) will be provided by the Office upon request and payment of the necessary fee.

FIG. 1 : Front top left perspective view of an electrical connector showing a first embodiment of the new design;

FIG. 2 : Front plan view thereof;

FIG. 3 : Back plan view thereof;

FIG. 4 : Top plan view thereof;

FIG. 5 : Bottom plan view thereof;

FIG. 6 : Left plan view thereof;

FIG. 7 : Right plan view thereof; and,

FIG. 8 : Front top right perspective view thereof.

Broken lines are used to illustrate portions of the electrical connector that form no part of the claimed design.

**1 Claim, 8 Drawing Sheets
